UNITED STATES PATENT OFFICE.

WILLIAM SEYMOUR, OF PATERSON, NEW JERSEY.

STREET-SWEEPING MACHINE.

No. 918,802.

Specification of Letters Patent. Patented April 20, 1909.

Application filed March 8, 1907. Serial No. 361,334.

To all whom it may concern:

Be it known that I, WILLIAM SEYMOUR, a citizen of the United States, and resident of Paterson, in the county of Passaic and State 5 of New Jersey, have invented certain new and useful Improvements in Street-Sweeping Machines, of which the following is a specification.

The object of my invention is to provide a 10 new and improved street sweeping machine which is simple in construction, strong and durable, effective and reliable in use and which collects the sweepings and delivers them into a receptacle.

15 In the accompanying drawings, in which like letters of reference indicate like parts in all the figures:—Figure 1 is a side elevation of my improved street sweeping machine; parts being broken away and others shown 20 in section. Fig. 2 is a vertical transverse sectional view on the line 2—2 of Fig. 1. Fig. 3 is a horizontal sectional detail view on the line 3 of Fig. 1. Fig. 4 is a side elevation of a modified construction of my improved 25 machine, as adapted for and driven by power, parts being broken away and others shown in section. Fig. 5 is a horizontal sectional view on the line 5—5 of Fig. 4.

This sweeping machine is built essentially 30 as a vehicle and as shown at Fig. 1 this vehicle is to be pulled by horses and as shown in Figs. 4 and 5 it is a power driven machine. The vehicle frame A is constructed in any conventional manner but preferably with 35 metal side bars suitably connected and braced and mounted in the conventional way on the front wheels B and rear wheels B'. The rear wheels are connected to turn with their axle B² and on this axle is mounted a clutch section C in such a manner that it can rotate 40 with the axle and slide lengthwise on the same in any well known or conventional manner and this clutch section C can be engaged with a clutch section C¹ mounted 45 loosely on the axle B² and made integral with a cog wheel D which is engaged with a smaller cog wheel D¹ suitably mounted on a stud or shaft on the frame of the machine. A sprocket wheel is connected with the cog 50 wheel D¹ and over the same a sprocket chain E passes which also passes over a sprocket wheel E¹ secured on a sleeve or hub G¹ of a cylinder or drum G mounted loosely on a shaft F secured on the frame of the machine.

When the vehicle is propelled this drum G is 55 rotated in the direction of the arrow, x, Fig.

1. In this drum one or more, in this case three, radially moving blades H are mounted which are guided in their radial movements by pins H¹ projecting from the ends of the 60 blades through the radial slots H² in radial spokes or arms H³ of the drum. A pair of helical springs H⁴ are attached to each end of each blade and to the interior of the drum and these springs serve to pull the blades outward so as to cause them to project from the 65 drum through longitudinal slots in the circumference of the drum. A roller I is mounted on each end of each blade and these rollers can travel on the inner surface of a 70 fixed cam track I¹ of which one is provided at each end of the drum, said tracks being supported by suitable arms I² from the main frame.

A chute J, substantially semi-circular in 75 shape and of a width equal to the length of the drum embraces the front semi-cylindrical half of the drum and its upper end is in communication with a substantially cylindrical chamber J¹ which is also in communication with the top of a box J² located on the frame of the machine above the rear axle and which box J² serves to receive the sweepings. This chute J is closed at its outer side but its inner side is open, the closure of the inner side being formed by the outer circumferential face of the drum G. The lower end of the chute J, which end is curved downward and rearward, is open and is directly in front of a large cylindrical horizontally mounted sweeping brush K extending transversely to the frame of the vehicle and supported in arms K¹ mounted pivotally on the transverse shaft F. These arms are pulled upward by springs K² attached to the 95 frame of the vehicle and to the arms. These arms K¹ are each connected by an upwardly extending pivoted link K³ with a lever K⁴ pivoted at K⁵ on the frame of the machine and terminating in a handle K⁶ behind the 100 driver's seat K⁷, the said two levers K⁴ on the two sides of the machine being both connected with a single handle so that the driver can, by raising this handle and locking it in place readily hold the brush K off the 105 ground. This brush K is rotated by means of a sprocket chain L passing over a sprocket wheel on the axle of the brush K and over

a sprocket wheel L^1 on the hub G^1 . At the lower end of the chute J a stiff canvas, rubber or leather apron M is pivoted at M^1 in such a manner that its free end can rest upon the ground directly in front of the brush K so as to prevent the brush K from throwing the sweepings forward beneath the lower end of the chute. A second apron M^2 also made of heavy canvas, rubber or leather is also pivoted at M^1 to the underside of the chute and extends downward to the ground in front of the apron M so that when any irregularity in the road or street or stones is encountered the said aprons can swing up without injuring or unduly jolting any parts of the machine. When the apron M is swung up by a stone or irregularity in the road or the street, the apron M^2 rests upon the surface of the street thus preventing the sweepings thrown forward during the short interval of time that the apron M is lifted off the street. A rotating brush N is mounted in the chamber J^1 and is driven from a sprocket wheel on the rear axle and a sprocket wheel 25 on the shaft of this branch N by means of a sprocket chain N^1 .

At each side of the machine a vertical shaft O is mounted which carries at its upper end a beveled cog wheel O^1 engaging a beveled cog wheel O^2 mounted on a stud projecting from the curved chute J and driven by a sprocket chain O^3 , from a sprocket wheel O^5 on the hub G^1 , so that the vertical shaft O is rotated. Three brushes P having downwardly extending bristles are each attached to the lower end of a rod P^1 mounted to move up and down in two disks P^2 secured on the lower part of the vertical shaft O between which disks a helical spring P^3 surrounds 35 each rod P^1 and serves to push it and its brush downward. On the upper end of each rod P^1 an arm Q is secured which runs on a fixed circular cam track Q^1 having a cam projection Q^2 so that the brushes P while in contact with the street are rotated in circular lines but before the completion of each circle are raised by the cam projection Q^2 so as to leave the pile of sweepings on the street in the track of the main rotary brush K .

50 The operation is as follows:—Such sweepings as have been loosened and swept into a number of piles by the rotating brushes P encounter the rotary brush K which throws them upon the apron M and into the lower open end of the chute J . Whenever a blade H arrives at the bottom of the drum G a short distance up from the lower end of the chute J it is forced outward by its springs H^4 and during its upward movement with the 55 rotating drum carries the sweepings in advance of it upward and upon the face of the drum and within the chute and when said blade H arrives almost near the top of the drum the cam track I^1 acting upon the rollers

I of said blade gradually withdraws the blade 65 and holds it withdrawn into the drum until it arrives slightly beyond and in front of the bottom of the chute at which point the blade is again ejected into the chute J . These blades with the outer surface of the drum 70 thus carry the sweepings through the chute J to the upper end of the same and into the chamber J^1 from which they are swept by the rotary brush N and into the receptacle J^2 . In the construction shown in Figs. 4 and 5 a 75 motor R is provided on the front of the machine and also a steering wheel R^1 by means of which the front wheels can be shifted in the conventional manner for the purpose of steering. The rear wheels are driven by a 80 sprocket wheel and a sprocket chain S and intermediate gearing from the motor and the drum G is driven from the motor by means of intermediate gearing, otherwise the construction of the machine is not altered. The 85 usual clutches as represented at W , are provided for the purpose of starting and stopping parts, etc.

Having described my invention what I claim as new and desire to secure by Letters 90 Patent is:—

1. In a street sweeping machine, the combination with a rotary brush, of a curved chute having its lower open end in front of the brush, a rotary drum, the periphery of 95 which forms one wall of the chute and blades on said drum extending into the chute, and means for withdrawing said blades from the chute at intervals substantially as set forth.

2. In a street sweeping machine, the combination with a rotary brush, of a curved chute having its lower open end in front of the brush, a rotary drum, the periphery of which forms one wall of the chute and blades on said drum extending into the chute, and a 100 cam for withdrawing said blades from the chute, substantially as set forth.

3. In a street sweeping machine, the combination with a rotary brush, of a curved chute having its lower open end in front of 110 the brush, a rotary drum the periphery of which forms the inner wall of the chute and blades on said drum extending into the chute, means for projecting blades into the chute and a cam for withdrawing the blades from 115 the chute, substantially as set forth.

4. In a street sweeping machine, the combination with a frame and a rotary brush, of a curved chute having its lower open end in front of the brush, a rotative drum forming 120 the inner walls of the chute, blades extending from the drum into the chute, and a sweepings receptacle connected with the upper end of the chute, substantially as set forth.

5. In a street sweeping machine, the combination with a frame, of a rotary brush, a curved chute having its lower end in advance 125 of the brush, a rotary drum forming the inner

wall of the chute, which drum has slotted radial arms, blades guided in said arms to move radially, springs for pulling said blades outward, rollers on the ends of the blades and 5 fixed cams for said rollers, substantially as set forth.

Signed at New York city in the county of

New York and State of New York this 7th day of March A. D. 1907.

WILLIAM SEYMOUR.
